LIPSTICK CONTAINER

Allan C. Hoffman, Milldale, Conn., assignor to
 Scovill Manufacturing Company, Waterbury,
 Conn., a corporation of Connecticut

Original application December 22, 1936, Serial No.
 117,137. Divided and this application Febru-
 ary 10, 1938, Serial No. 189,740

3 Claims. (Cl. 206—56)

This invention relates to certain improvements in containers for lipsticks, eyebrow pencils and similar soft pasty cosmetics, and particularly to a type of container in which the cosmetic stick is supported in a carrier which is moved from an enclosed casing to expose the stick for use and then withdrawn into the casing and covered by a cap member; this type of dispenser being generally known as a swivel-type lipstick container.

5 This invention is a division of a prior application filed December 22, 1936, Serial #117,137, issued as Patent No. 2,131,046, September 27, 1938, and has been made the subject of a separate application under official requirement.

10 It is the principal object of this invention to provide a round or tubular type of cosmetic container of the above nature in which means are provided for interlocking the rotatable cosmetic propelling means of the casing with the cover when assembled thereon, and especially to provide 15 for such interlocking means which may be readily applied to a standard or stock lipstick with the minimum of changes and parts.

15 With these and other objects in view, the invention consists in certain novel features of construction, combinations and arrangements of parts as will be more fully disclosed in connection with the accompanying drawing and as set forth in the annexed claims.

20 In the drawing—

Fig. 1 is a partial side elevation and partial sectional view of a lipstick container embodying the principles of this invention and showing the parts in their normal assembled locked position.

25 Fig. 2 is a perspective view of the lipstick container showing the cover detached.

Fig. 3 shows fragmentary separated views of cover and container improvements showing a modification of the construction.

30 Dispensing containers of the class generally known as swivel type lipsticks are a construction well known in the art and a brief description of the same is considered sufficient for a disclosure of the subject matter of this invention. Refer-
 35 ging now to the drawing in which like numerals refer to corresponding parts throughout the several views the numeral 10 refers generally to a cylindrical type of dispensing container. In its construction the container 10 consists essentially of an outer tubular casing 11, an inside body shell 12 and a spring sleeve 13 disposed therebetween and adapted to be frictionally retained by the outside shell 11. The sleeve 13 is formed with a helical slot 14 and the inside shell is provided 40 with a longitudinal slot 15 in which slots 14 and

15 is cooperatively engaged the head of a pin 16 affixed to a carrier cup 17 holding the cosmetic stick 18. By manipulating or turning the inside shell 12 relative to the outside shell 11—the former for manipulating purposes being provided with an enlarged knurl head 19 at one end—the carrier cup may be axially advanced or retarded within the container 10 depending on the direction or rotation of the head 19. When not in use, the container 10 may be conveniently 10 closed by a tubular cover 20 adapted to telescope over substantially the entire length thereof.

As stated in the objects the primary reason of this invention is to reconstruct a standard tubular container in such a manner as to retain its 15 general cylindrical appearance and provide an interlocking means between the relative rotative members when the container is in closed position. More specific means is provided whereby the inside shell 12 is interlocked against rotation 20 within the outer casing 11 by mere assembly of a cap 20 upon the container 10.

Between the knurl head 19 and the body proper of the inside shell 12 there is formed an intermediate expanded section 21 formed with a series of longitudinal serrations or flutes 22 and the lower end of the slip cover 20 is likewise expanded as at 23 and formed with correspondingly shaped flutes 24. The upper portion of the expanded section 21 above the flutes 22 is slightly 30 beveled or chamfered as at 25 to facilitate the guiding of the flutes 24 on the cover 20 into proper interengagement with the corresponding flutes 22 on the shell 11. Thus it will be evident that when the cover 20 is in complete assembled position 35 access to the outer shell 11 will be impossible and in addition the inside shell 12 will be interlocked with the cover 11 positively assuring no rotation between the relatively rotative members.

In case it is objectionable to have the flutes or serrations visible on the lower end of the cap 20, as in the first form, this may be avoided by a construction disclosed in Fig. 6 wherein the lower end of the cap 20a is provided with an inner attached collar 26 having the interlocking flutes 27 positioned within the inner end of the cover 20a adjacent the open end. The collar 26 may be rigidly secured by being spun over and forming an attached bead 28 around the lower 45 annular end of the cover 20a.

While this invention has been shown and described in two forms, it will be understood that other changes and variations may be made in the specific constructions shown and described with- 50 55

out departing from the scope of the invention as defined in the appended claims.

What is claimed is—

- 5 1. In a dispensing cylindrical container of the character disclosed, an outer casing, an inner shell rotatable within said casing, a carrier slideable within said shell, means for advancing and retracting said carrier coincident with the rotations of said shell, an exposed operating head 10 provided at the lower end of said shell, an intermediate expanded portion formed between said head and said shell, a cylindrical closure cap adapted to telescope over the outside of said casing, a cylindrical sleeve secured to and disposed just within the open end of said cap and having a flanged portion rolled or beaded about the open end of said cap as a means of permanent attachment, said sleeve being formed with flutes corresponding to said first mentioned flutes whereby non-rotatable engagement will be effected between said cap and inner shell when in assembled position.
- 15 2. In a dispensing cylindrical container of the character disclosed, an outer casing, an inner shell rotatable within said casing, a carrier slideable within said shell, means for advancing and retracting said carrier coincident with the rotation of said shell, an exposed operating head provided at the lower end of said shell, an intermediate expanded portion formed between said head and said shell and having a series of undulate flutes, a cylindrical closure cap adapted to

telescope over the outside of said casing, and a cylindrical sleeve secured to and disposed just within the open end of said cap and having a flanged portion rolled or beaded about the open end of said cap as a means of permanent attachment, said sleeve being formed with flutes corresponding to said first mentioned flutes whereby non-rotatable engagement will be effected between said cap and inner shell when in assembled position.

- 20 3. In a dispensing cylindrical container of the character disclosed, an outer casing, an inner shell rotatable within said casing, a carrier slideable within said shell, means for advancing and retracting said carrier coincident with the rotation of said shell, an exposed operating head provided at the lower end of said shell, an intermediate expanded portion formed between said head and said shell and having a series of undulate flutes, a cylindrical closure cap adapted to telescope over the outside of said casing, and a sleeve member secured within the open end of said cap, said sleeve being formed with flutes corresponding to said first-mentioned flutes, both sets of flutes having their adjacent ends beveled off to facilitate and lead the fluted sections into relative interlocking engagement with each other when assembling the cap upon the container.

ALLAN C. HOFFMAN.
